UNITED STATES PATENT OFFICE.

EDUARD ALTHOFF, OF OBERHAUSEN, GERMANY.

PNEUMATIC ROCK-DRILL.

1,079,735.

Specification of Letters Patent.

Patented Nov. 25, 1913.

Application filed December 26, 1911. Serial No. 667,911.

To all whom it may concern:

Be it known that I, EDUARD ALTHOFF, a subject of the King of Prussia, Germany, residing at Oberhausen, Germany, have invented a new and useful Pneumatic Rock-Drill, of which the following is a specification.

When pneumatic rock-drills with automatic feed are to satisfy all reasonable demands, they must coöperate with their guide-bar in such a manner that a regular feed is assured, even when the axis of the drill-hole deviates up to 90° above or below the horizontal, and besides this, the guide-bar must not only offer the possibility of directing the drill to any point of the cross-sectional area of the tunnel, gallery and the like to be constructed, but must also permit the axis of the drill-holes to form different angles with the longitudinal axis of said tunnel, gallery and the like. To obtain this, the connection between the rock-drill and the guide-bar must be based upon such a principle, that the feed of the rock-drill can be suitably increased or diminished in order to adapt itself readily to any direction of the drill-hole or hardness of the rock. This is necessary for the reason, that in the first instance the weight of the rock-drill influences the work of the drill in a different way when a drill-hole is directed upwardly than when directed downwardly, as will be readily understood; whereas in the second instance the reaction of the drill will be more powerful on hard rock than on the softer varieties thereof. To these difficulties must be added the inconvenience caused by dirt and grit unavoidable in rock-drilling, which will clog all parts of the drilling apparatus and will of course be found particularly trying and inconvenient on the guide-bar. The connection between rock-drill and guide-bar must therefore be designed with a view to eliminate the drawbacks originating from a dirty and perhaps greasy guide-bar to enable the feed-mechanism to take at all times and under the most trying conditions give a sure grip on the guide-bar.

The object of my present invention is to satisfy these demands which I accomplish by arranging upon the guide-bar carrying the rock-drill a clamping-shoe which takes hold of said guide-bar without the least delay as soon as the rock-drill tries to escape backward upon delivering the blow. To

accomplish this without fail I employ on the one hand this backward motion of the rock-drill itself and insert on the other hand between the latter and said clamping-shoe, an elastic element adapted to retain these parts at all times in touch one with another. However, in order to utilize any suitable part of the forward motion of the rock-drill, partly generated by said elastic element, partly by a clamping-lever carrying the latter, and partly by the power generated by the driving-medium employed to retract piston and striking-pin while acting upon the forward annular cylinder-cover as far as this is made possible by the inertia of said piston and its striking-pin, I provide said clamping-shoe with adjusting-means adapted to appropriate any desirable part of the forward motion of the rock-drill for a permanent advance of the latter. The clamping-shoe employed must of course accommodate itself to the shape of the guide-bar that supports it, which in turn may be of the simple variety usually secured by a wedge in the rock, or it may be executed as a compound-bar. The latter makes it possible, by employing a boring-bracket, for the drill to not only be directed to any point of the cross-sectional area of the tunnel or gallery to be driven forward but the direction of the drill-holes can also be made to run at different angles to the axis of such tunnels, galleries, etc.

In the accompanying drawings:—Figure 1 is an elevation partly in section of a pneumatic rock-drill constructed in accordance with my present invention and showing a clamping-shoe which operates in a channeled guide-bar. Fig. 2 is a similar view of the pneumatic rock-drill provided with a clamping-shoe as well as with a clamping-ring simultaneously operating upon a guide-bar carried by an adjustable boring-bracket. Fig. 2' is a side view partly in section of the clamping ring and adjoining parts. Fig. 3 is another similar view of the pneumatic rock-drill sustained by a guide-bar carried by a boring-bracket whose adjustable arm is bent to form an obtuse angle to permit of drill-holes being made to run at different angles to the axis of the tunnel, gallery or the like to be driven into the rock. Fig. 4 is an end view of the clamping shoe of Fig. 1; Fig. 5 a detail of the adjusting screw and coöoperating parts; Fig. 6 an end view thereof; Fig. 7 a detail of the friction

block coöperating with the clamping shoe; and Fig. 8 a detail of the clamping plate of Fig. 3.

The guide-bar 1 shown in Fig. 1 is V-shaped in cross-section and is secured in the rock 3 by means of the wedge 2 which slides upon the sloping base 4 arranged within the channel of said bar. The pneumatic rock-drill 5 of any suitable construction is connected with the guide-bar 1 by means of the foot 6 and foot or abutment 7 of Y-shaped form which feet are securely attached to said rock-drill by the aid of the side-rods 8. Since the feet only permit of the rock-drill being moved back and forth upon the guide-bar 1, it may be used either in a standing or in a hanging position.

The channel 9 of the guide-bar 1 serves for the reception of the clamping-shoe 10 the sides of which are of course slanted to suit the inclined inner faces of the cheeks 11 and 12, Fig. 4. The clamping-shoe 10 carries on its rear-end two lugs 13 between which the clamping-lever 14 is rotatably supported by the pin 15. To the upper end of said lever is secured a spring 16 which serves as a cushion and always remains in contact with the handle 17 of rock-drill 5. The lower-end of the clamping-lever 14 is forked to straddle the clamping-shoe as well as the guide-bar and carry the friction-block 18 which is supported by the pin 19. The hole 20 serving for the reception of the latter is so arranged that the four friction-faces 35 of said block are arranged at different distances from the center of the hole 20 and can thus be brought consecutively into contact with the underside of the guide-bar as the wear and tear of the work may require this. The friction-surfaces of said block may be roughened in any suitable manner if this should be deemed necessary.

In order to regulate the feed of the rock-drill to suit any particular direction of the drill-hole or hardness of rock an adjusting-screw 21 is arranged in the extension 22 of the clamping-shoe 10 and can be manipulated by the weighted lever 23. The latter is rotatably attached to the head 24 of the screw 21 by means of the forked plug 25 rotatably but not slidingly held in said screw-head. The lever 23 is further provided with a nose 26 which can be consecutively inserted into the radial slots 27 of the head 24. To prevent the lever 23 from rotating and thus leaving the slot the head 24 is provided with a semicircular groove 28 and the nose 26 with a hole 29 so that when the groove 28 and the hole 29 coincide a split-pin 30 attached to a small chain 31 may be inserted into said hole and thus retain said lever locked no matter what the position of the rock-drill may be. When released by the operator, lever 23 will by its own weight 65 permanently maintain the position shown

in Fig. 1, thus preventing an accidental change in the adjustment of screw 21.

The operation is as follows:—It is a well known fact that the rock-drill rebounds backward when the drill 32 receives the blow. At the beginning of this backward motion of the rock-drill the handle 17 of the latter commences to tension the spring 16 which up to this moment was only sufficiently tensioned to keep rock-drill and clamping-shoe in feeling contact with each other. The spring 16 will be gradually compressed and the lever tilted when the resistance of the spring has reached a point to transfer the pressure exerted upon it by the handle 17 fully to the lever 14. At the moment this takes place the lever 14 swings on the pin 15 and thus presses the friction-block 18 against the underside of the guide-bar 1 and simultaneously presses the clamping-shoe from above into the channel 9 of the guide-bar. The friction created hereby suffices to arrest the rock-drill instantaneously. Care must however be taken to prevent the pressure-components from becoming powerful enough to bind the clamping-shoe too hard in the channel. This may be readily prevented by giving the inner faces of the cheeks 11 and 12 the proper inclination. While arresting the backward motion of the rock-drill energy was stored up in the spring on the clamping-lever, which energy manifests itself in throwing the rock-drill forward in the opposite direction. In this action said spring 16 is aided by the action of the compressed air which in the meantime has been admitted to the front side of the piston (not shown) in order to retract said piston and the striking-pin carried thereby. The whole force thus generated will however not come hereby under consideration, but simply that part thereof due to the inertia of the piston and its striking-pin and the friction caused by the latter in its guides. If the whole forward travel of the rock-drill is represented by the value " w ," and that part thereof destined for the actual forward feed of the rock-drill by the value " a ," then the remainder will be $=w-a$. If this part be represented by the value " b " 115 then it is evident that during this part of travel the clamping-shoe must remain at rest. To vary the values a and b to suit any given conditions the distance between the extension 22 and the abutment 7 must be altered accordingly i. e. the point of the screw 21 must approach the extension 22 when the value b is to be increased and recede therefrom when the value a is to be increased. The spring 16 remains readily in contact with the handle 17 during this adjustment since practically only very small lineal displacements of the clamping-shoe need be considered. In view of the fact that the distance traveled backward by the 130

point of contact between the handle 17 and the spring 16 until the latter is sufficiently tensioned to swing the clamping-lever to the right, to effect its gripping operation, is equal to the distance to which the point of the screw 21 at this particular moment is retracted from the front-face of the abutment 7 it follows that both are identical and represent the value b . After the backward motion of the rock-drill has been arrested and the latter has started to accomplish its forward travel $=w$, the clamping-shoe will remain at rest until the abutment 7 strikes the point of the screw 21 *i. e.* after the value b has been attained the rock-drill and clamping-shoe will proceed simultaneously until both come to a stand-still. It is therefore evident that the value a can be fixed by varying the value b . As in the meantime the driving-medium has been led again behind the piston of the rock-drill the latter will move again to the right until the handle 17 will tension the spring 16 anew and thus compel the clamping-lever 14 to operate the clamping-shoe 10 again. The rock-drill will thus be arrested again, but at a distance equal to the value a nearer to the rock 2 or what amounts to the same, in front of the point where it was arrested at the preceding blow. After this the rock-drill will be thrown forward again and after having traveled over its way $w=a+b$ be thrown back again with the result explained above. This play of the rock-drill will continue until the driving-medium is shut off and the operation of the drill 32 ceases.

Exactly the same operations will take place in the pneumatic rock-drills 5 shown in Figs. 2 and 3 notwithstanding the fact that the clamping-shoes are somewhat different in shape to the one shown in Fig. 1. In the first place the guide-bar 33 of Fig. 2 is not channeled neither secured directly in the rock but carried by an arm 34 of a boring-bracket 35, the plug-member 36 of which is secured in the rock by a wedge 37. Member 36 is provided with a head 36^a against which arm 34 is held by a wedge or key 38 engaging a corresponding slot formed in the protruding end of said member. To securely hold the guide-bar 33 it suffices to slip the eye of the latter over the arm 34 and let the weight of the rock-drill do the rest. Keys or binding-screws may of course be employed if deemed necessary. This simple connection of the guide-bar with said bracket already suffices to permit of holes being drilled on four radial lines by simply altering the position of the plug-members 36. In case this should not suffice the key 38 is eased sufficiently to swing the arm 34 into the desired position and there secure it again by driving the key 38 home. The feet 6 and 7 employed in Fig. 1 are here replaced by other elements the one by the clamping-

ring 39 and the other by the extension 40 of the cylinder-cover 41. The clamping-shoe 42 is in this instance arranged beneath the guide-bar 33 and the clamping-lever 43 thereof is provided with a clamping-foot 44. 70 The clamping-lever 43 is U-shaped in cross-section like the clamping-lever 14 in Fig. 1 and carries, like the latter, a spring 45, besides which it is provided with lateral guide-lugs 46. In the extension 47 of the clamping-shoe 42 an adjusting-screw 48 is arranged the extension 49 of which passes through the said cover extension 40. This screw may be adjusted by means of the hexagonal-shoulder 50 and secured in any given position by the check-nut 51. The clamping-ring 39 is loosely seated upon the pintle 52 of the boss 53 in such a manner that it will be caused to grip the guide-bar 33 during the backward motion of the rock-drill while trying to turn clock-wise. The corner 54 will hereby try to penetrate into the top-face of said guide-bar whereas the corner 55 will try to do the same in regard to the bottom-face thereof. The result obtained hereby is, that the clamping-ring 39 will ease the gripping-work of the clamping-shoe 42 and thus aid the latter. The force required by the clamping-ring for doing its work is furnished by the weight of the rock-drill. The pin 56 prevents the clamping-ring 39 from slipping from the pintle 52.

Since the working of the clamping-shoe 42 is identical with that of the clamping-shoe 10 of Fig. 1, it only remains to direct attention to fact that on tilting the clamping-lever through the instrumentality of the backward-motion of the rock-drill, the clamping-foot 44 will be pressed against the top-face of the clamping-bar 33 and thereby draw the inner face of the clamping-shoe 42 against the bottom-face of the guide-bar. The inner face of the clamping-shoe may be roughened in any manner, if so desired. It is evident, that the guide-bar 1 of Fig. 1 might be employed in connection with the boring-bracket 35, since all that is necessary for this purpose is to provide it with an eye adapted to be slipped over the arm 34. 100

The pneumatic rock-drill shown in Fig. 3 is mounted upon the guide-bar 59 by the aid of the foot 57 and the eye 58. The guide-bar itself is mounted in this instance on the bent arm 60 of a boring-bracket 6^a in all other respects similar to the one shown in Fig. 2. The bent arm 60 can be secured to the plug-member 36 in any desired direction by means of the nut 62 and offers this advantage over the straight arm 34 that by a simple face-about turn, said arm, guide-bar and everything carried by it may be brought into the position indicated by dotted lines in Fig. 3. This peculiarity may be advantageously appropriated for retaining the intended cross-sectional area of the tunnel, 110

115

120

125

130

gallery etc. without any extra manual labor, since the drill can be directed to such points that the drill-holes will start in close proximity to the boundary-lines of said cross-
5 sectional area and cross them more or less as their depth increases. The result will be, that after the charge has been ignited and the undermined part of the rock has been blown away said area will be rather in-
10 creased than decreased, or in other words, that by means of this arrangement all unnecessary manual labor will be avoided.

In the modification illustrated in Fig. 3, the clamping plate or shoe 64 carries a two
15 arm lever comprising a lower arm 65 and an upper bent arm 67, 70, said lever combining the parts 39 and 43 shown in Fig. 2. Plate 64 is roughened at its lower side and has opposed lateral recesses 66 (Fig. 8) which
20 serve for retaining said plate in position. The parts are assembled by slipping plate 64 in an upright position into a corresponding opening provided in the lower lever arm 65 and by then giving said plate a
25 quarter turn. The section 67 of the upper lever arm extends in substantial parallelism with bar 59, while bent section 70 projects upward at right angles to section 67. A slot 68 of section 67 receives the stem 69 of
30 eye 58, and section 70 carries a rebound spring 71 and lateral guides 72. To arm 65 is secured by bolts 74 a check plate 73 which may be adjusted relatively to guide bar 59 by means of a screw 75 having a squared
35 end 76. The latter enters into a slot 77 of the plate 73 and is held thereby in such a manner that it cannot be rotated so that to advance the plate 73 it becomes necessary to unscrew the bolts 74, lift the plate 73 and
40 replace these parts again after the screw 75 has been set. To ease the work of the screws 74 the underside of the plate 73 may be roughened as indicated in Fig. 3. A spring 78 aids the lever 65, 67, 70, in retaining
45 its most advantageous position on the guide-bar. The regulation of the feed is accomplished by means of the set-screw 79 which is held by eye 80 secured to arm 67 and can be secured after each adjustment by
50 means of the check-nut 81.

When on moving backward the rock-drill comes into contact with the spring 71 and thus tensions it until it can push the arm 70 backward, lever 65, 67, 70 will swing on the
55 edge 82 of lever arm 65 so that the upper edge 84 of check plate 73 will be forced against the lower side of bar 59. In this way shoe 64 will be clamped to this bar whenever drill 5 rebounds.

60 From the foregoing it will be manifest that the backward motion of the rock-drill

of any kind may be utilized to block its own way by compelling the clamping-shoe to grip the guide-bar, that further a pre-determinable fraction of the forward motion of the rock-drill can be utilized for the forward feed of the rock-drill and that the backward motion of the rock-drill may be brought to a close when the latter reaches a point which lies in advance of the arresting-
65 70 point reached at the preceding blow to the extent equal to its feed.

I claim:—

1. A device of the character described, comprising a bar, a clamping shoe movable along said bar, a clamping lever pivotally connected to said shoe, a rock drill slidably supported by said bar, means for intermittently advancing said drill, a rebound spring intermediate said lever and drill, and means on said lever for locking the clamping shoe to the bar. 75

2. A device of the character described, comprising a bar, a rock drill adapted to be intermittently advanced along said bar and having an abutment, a clamping shoe movable along the bar, a clamping lever pivotally connected to said shoe, a rebound spring intermediate the drill and lever, and drill-advancement adjusting means movable with 80 the shoe and adapted to be engaged by the drill-abutment. 85

3. A device of the character described, comprising a bar, a rock drill adapted to be intermittently advanced along said bar and having an abutment, a clamping shoe movable along the bar, a clamping lever pivotally connected to said shoe, a friction block carried by the lever and adapted to engage the bar, a rebound spring intermediate the 95 drill and lever, and an adjusting screw tapped into the shoe and adapted to engage the drill-abutment. 100

4. A device of the character described, comprising a bar, a rock drill adapted to be intermittently advanced along said bar and having an abutment, a clamping shoe movable along the bar, a clamping lever pivotally connected to said shoe, a friction block carried by the lever and adapted to engage the bar, a rebound spring intermediate the 105 drill and lever, an adjusting screw tapped into the shoe and adapted to engage the drill-abutment, a slotted head on said screw, and a swinging gravity lever pivoted to said head and adapted to engage the head-slots. 110

Signed by me at Barmen, Germany, this 14th day of December 1911.
